UNITED STATES PATENT OFFICE.

SOLOMON H. GOLDBERG, OF CHICAGO, ILLINOIS, ASSIGNOR TO THE HUMP HAIRPIN MANUFACTURING COMPANY, OF CHICAGO, ILLINOIS, A CORPORATION OF ILLINOIS.

HAIRPIN CONTAINER.

Application filed July 15, 1918. Serial No. 244,829.

To all whom it may concern:

Be it known that I, SOLOMON H. GOLDBERG, a citizen of the United States, residing in the city of Chicago, county of Cook, and State of Illinois, have invented certain new and useful Improvements in Hairpin Containers, of which the following is a specification.

This invention relates to improvements in hairpin containers and has for its object to provide simple and economical means for holding a plurality of hairpin bundles of different sizes in proper alignment in the box or other container but in such a way that they may be readily inserted in or removed from the container.

In the drawings:

Fig. 1 is a top plan view of the box or container with the hairpin bundles in position but with the top of the box removed.

Fig. 2 is a longitudinal section through the box with the pins omitted.

Fig. 3 is a sectional detail taken on lines 3-3 of Fig. 1 looking in the direction of the arrows but showing the top in place.

Fig. 4 is a detail view of a portion of the spring gripping retaining strip.

Referring to the drawings, 1 designates the box having a bottom 2, side walls 3 and removable slip cover top 4. In the box is seated a retaining member designated as a whole 5 and comprising base members 6 which may, if desired, be pasted to the bottom of the box, and a centrally disposed vertical retaining strip 7. This strip may be formed by bending the base portions centrally upon themselves in the manner clearly shown in Fig. 3. The retaining strip ex-

tends diagonally across the box and is provided with apertured spring gripping fingers 8, the apertures being of successively increasing size as shown clearly in the drawings. The upper edges of the spring gripping fingers preferably approach each other so as to fit more or less around the bundle of hairpins. The arrangement is such that when the bundle of hairpins are placed in the box, the closed end of the pins will preferably lie against the one wall of the box and the bundle of pins fit between the corresponding spring gripping fingers. The pins of each bundle are held together by means of a band 9. The band 9, it will be seen, in the drawing, lies between the retaining strip and the wall of the box and serves to limit the movement of the pins away from the wall of the box adjacent the heads of the pins. It will also be seen that the bundles of hairpins of different sizes can be used. The construction not only gives a neat and attractive arrangement of the pins but insures of the hairpin bundles being at all times in their proper place in the box so there is no liability of their being disarranged during their shipping.

I claim as my invention:

A hair pin container comprising a box portion and a double retaining wall provided with a series of spaced slotted apertures therein forming spring gripping fingers to hold hair pin bundles in position, said retaining wall extending diagonally across the box portion whereby a plurality of bundles of hair pins of different sizes or lengths may be held in alignment.

SOLOMON H. GOLDBERG.
